SAFETY RAZOR

Joseph E. McWilliams, New York, N. Y.

Application August 13, 1932, Serial No. 628,689

4 Claims. (Cl. 30—12)

This invention relates to safety razors of the double-edged, flexible blade type, and its object is to improve the blade positioning and clamping means of such razors. In all razors of this type, so far as I am aware, the cap or clamping plate is provided with studs, bars, or other projections which enter corresponding holes or recesses in the blade and guard plate, and thus definitely fix the relative positions of these elements, or the guard plate is provided with projections which enter corresponding openings in the blade and thus locate the blade with reference to the guard, and the blade in turn is definitely fixed with reference to the cap.

10 In accordance with the present invention I provide the ends of the cap with depending flanges which overhang the ends of the guard plate and approximately locate the cap with reference to the guard. No other locating means are employed, except of course, the central threaded pin which passes through the guard and engages the handle. These depending flanges cooperate with tongues or notches on the ends of the blade and locate the blade with reference to the cap.

15 The razor illustrated in the drawing comprises a cap or clamping member 1, a guard plate 2 and a handle 3. A flexible double-edged blade 4 is held between and flexed by the cap and guard as illustrated in Figure 3. Assembly of the parts is effected through a screw-threaded pin 5 depending from the middle of the cap 1, passing through a slot 6, or other suitable opening in the 20 blade, and a hole 7 in the guard plate and threadedly engaging the upper end of the handle, all as illustrated in Figure 3.

The ends of the cap are provided with depending flanges 8 which overhang the ends of the guard which are smooth and provided with neither recesses nor projections. I have illustrated a single flange at one end of the cap and a double, or notched, flange at the other designed to receive a corresponding notch 9 and tongue 10 25 on the blade. The precise form of flange is not material, however. Either the single or double flange may be used on either end with a corresponding modification in the form of the blade.

In order that the blade may be flexed between the guard and cap, the upper face of the guard is made cylindrically convex and the under face of the cap concave. This is the usual construction in razors of this type. I provide sufficient play between the flanges and the ends of the guard and between the threaded pin and the guard to permit the guard and cap to seat themselves naturally in proper position as they are drawn together to flex the blade. This natural seating follows from the curvature of the parts and the limited play between them.

Another improvement of the present invention consists in mounting the guard plate for relative lateral adjustment. The hole in the guard through which the threaded pin on the cap passes to engage the handle is made sufficiently wider than the pin so that the lateral position of the guard with reference to the cap can be varied within limits before the parts are clamped into final operative position. The interengagement of blade and cap prevents lateral adjustment between them, except that due to flexure, and the cap being mounted upon the guard so as to permit of relative lateral movement it follows that the setting of the blade in relation to the guard can be varied at will.

In the accompanying drawing in which I have illustrated a preferred embodiment of my invention, Figure 1 is an end view of the assembled

razor; Figure 2 is a longitudinal, vertical section, on an enlarged scale, through the cap and guard taken along line 2—2 of Figure 1; Figure 3 is a transverse section on an enlarged scale taken along line 3—3 of Figure 5; Figure 4 is an enlarged perspective of the cap with the underside shown uppermost; Figure 5 is a bottom view of the guard with the handle removed, but with the blade and cap in position; Figure 6 is a bottom view of the cap with the blade in position and the 10 guard and handle removed and Figure 7 is a view of the blade itself.

The razor illustrated in the drawing comprises a cap or clamping member 1, a guard plate 2 and a handle 3. A flexible double-edged blade 4 is held between and flexed by the cap and guard as illustrated in Figure 3. Assembly of the parts is effected through a screw-threaded pin 5 depending from the middle of the cap 1, passing through a slot 6, or other suitable opening in the 20 blade, and a hole 7 in the guard plate and threadedly engaging the upper end of the handle, all as illustrated in Figure 3.

The ends of the cap are provided with depending flanges 8 which overhang the ends of the guard which are smooth and provided with neither recesses nor projections. I have illustrated a single flange at one end of the cap and a double, or notched, flange at the other designed to receive a corresponding notch 9 and tongue 10 25 on the blade. The precise form of flange is not material, however. Either the single or double flange may be used on either end with a corresponding modification in the form of the blade.

The blade makes a relatively snug fit with the 35 cap, but there is sufficient play between the guard and the flanges 8 and the pin 5 to permit the guard to take a natural seat when the parts are assembled into shaving relation, due to the cavity of the cap and the convexity of the guard.

In order to make the guard adjustable with reference to the shaving edge of the blade I make the hole 7, through which the pin 5 passes, of sufficient size to permit transverse movement of the guard with reference to the pin. In addition, the arcuate underface of the guard adjacent the hole 7 is countersunk at 11 to provide a flat seat for the end of the handle. In order to adjust the guard the parts are assembled in the position illustrated in Figure 3 and the guard moved slightly to one side before the final flexing pressure is applied. Thus, in the illustration, the distance A from the left-hand shaving edge to the outer edge of the guard is smaller than the corresponding distance B on the other side 50

of the razor. This adjustment, as well as the natural seating of the parts is made possible by the fact that the ends of the guard are smooth and do not interlock with the depending flanges 5 on the cap.

I claim:

1. In a safety razor comprising a concave cap having a centrally positioned threaded pin thereon, a convex guard having smooth ends and a slot receiving said pin, said slot permitting said guard to be adjusted laterally with respect to said cap, an interposed flexible blade having an opening receiving said pin and a handle engaging the pin and guard for drawing the cap and 10 guard together to flex said blade with said guard in different positions with respect to said blade, the combination of depending flanges on the ends of said cap interlocking with said blade, said flanges being spaced from said guard and the 15 curvature of said cap and guard causing the cap and guard to seat themselves in proper alignment during the blade flexing operation irrespective of the position of the guard laterally with respect to said cap.
2. In a safety razor comprising a concave cap having a centrally positioned threaded pin, a convex guard having smooth ends and a transversely extending slot receiving said pin, said slot permitting transverse movement of said 20 guard with respect to said cap, an interposed flexible blade loosely mounted with respect to said guard and having an opening receiving said pin, means engaging said pin and guard for drawing said cap and guard together to flex said blade with said guard in different positions with respect to said cap, the combination of depending flanges on the ends of the cap, said flanges overhanging the ends of the guard and engaging said 25

blade to position the blade with respect to the cap, there being clearance between the flanges and the guard and the curvature of the cap and guard causing the cap and guard to seat themselves in proper alignment during the blade flexing operation. 5

3. In a safety razor comprising a concave cap having a centrally positioned threaded pin, a convex guard having a slot to receive said pin, an interposed flexible blade having an opening to receive said pin and a handle engaging said pin and guard to draw said cap and guard together to flex said blade, said cap having depending flanges at its ends interlocking with said blade and clearing the ends of said guard, the curvature of said cap and guard normally serving to longitudinally align said cap and guard and said curvature and the clearance between said guard and said flanges and between the guard and pin permitting lateral adjustment of said guard with respect to said cap and blade to vary the projection of said blade beyond said guard. 10 15 20

4. In a safety razor comprising a concave cap, a convex guard having a transversely extending slot, an interposed flexible blade, a threaded pin on the cap extending through said slot in the guard and a handle engaging the pin and guard whereby the cap and guard are drawn together and the blade flexed, the slot in said guard permitting lateral adjustment of said guard, the combination of depending flanges on the ends of the cap interlocking with said blade and clearing the ends of the guard, the curvature of said cap and guard normally aligning the guard and cap during the blade flexing operation while permitting lateral adjustment of said guard with respect to said cap and blade. 25 30 35
